UNITED STATES PATENT OFFICE.

THOMAS J. CULLEN, OF JERSEY CITY, NEW JERSEY.

AUTOMATIC DRAFT-REGULATOR.

1,181,745.

Specification of Letters Patent.

Patented May 2, 1916.

Application filed April 9, 1915. Serial No. 20,201.

To all whom it may concern:

Be it known that I, THOMAS J. CULLEN, a citizen of the United States of America, residing at Jersey City, in the county of 5 Hudson and State of New Jersey, have invented certain new and useful Improvements in Automatic Draft-Regulators, of which the following is a specification.

The present invention relates to improvements 10 in automatic draft regulators particularly applicable for use in connection with steam heating systems for dwellings and other buildings.

The primary object of the invention is 15 the provision of automatically operated means by which the draft in the smoke flue may be governed by the quantity of water in an equalizing tank, and by which the draft may be cut off and be made to remain in 20 such condition so that the full benefit of the combustion of gases will be derived from the coal and not escape through the chimney, thus preventing consumption of the coal in the furnace due to negligence or carelessness 25 and insuring that the draft shall be turned on and off at the proper time.

The invention further has for its object 30 the combination and arrangement of means for operating the draft or retarding door to the furnace in connection with the draft in the smoke flue as will be hereinafter specified and set forth in my appended claims.

The invention consists in certain combinations and arrangements of parts whereby 35 the draft is regulated as will be hereinafter set forth.

In the accompanying drawings I have set forth a complete example of the physical embodiment of my invention constructed according 40 to the best mode I have so far devised for the practical application of the principles of my invention.

In the drawings: Figure 1 is a view in elevation, partly broken away for convenience of illustration, showing a furnace and equalizing tank of a steam heating system having my draft regulation device utilized thereon. Fig. 2 is an enlarged, detail, vertical sectional view of the automatic device 45 for locking the damper in closed position, and which is shown in position with the damper closed. Fig. 3 is a transverse sectional view of Fig. 2. Fig. 4 is a horizontal longitudinal, sectional view of Fig. 2.

In the preferred embodiment of my invention I have illustrated in the drawings

a standard type of steam heating furnace 1 of any well known type, in which the vacuum pipe 2 is passed through the furnace and into the smoke flue 3 in order to induce suction throughout the steam pipes and radiators of the heating system. 60

The draft through the smoke flue is controlled by the position of the damper 4 which is rotated by means of the toothed gear 5 and the toothed lever 6 which latter is pivoted at 7 outside the flue. This lever is operated through the medium of the chain 8 which passes over a pulley 9 supported in bracket 10 and through the automatic retaining device 11 to the float 12 in a separated compartment 13 in the pressure tank 14. An adjustable weight 6' is carried by the lever, and this weight is lighter than the float 12 and dominated thereby. 70 The tank also has a float 15 from which the chain 16 passes over pulleys 17 and 18 to the air or bottom draft door 19 of the furnace. The water rises from the boiler pipe 23 into tank 14 by pressure in boiler. To 80 the end of rack arm 20 a chain is attached to draft door 19 and also attached to rack arm 20. At point 21 the chain is carried to retard door 21' so that when the retard door is open draft door is closed, and when 85 draft door 19 is open retard door 21' is closed. It will also be understood that damper 4 will be closed and the proper amount of draft from the vacuum pipe 2 will be secured. Draft door 19 and also retard door 90 21' will open at the regulated time, as controlled by float 15. It will be further understood that float 15 will regulate the retard and draft doors only.

The float 12 is designed to permit closing 95 of damper 4 by weight 6' when the water in the tank rises at a pressure of 2 oz. or more. As the water rises float 12 is lifted to the proper starting point and thus the chimney draft is cut off, and when once cut off, the draft is automatically held cut off, or the damper closed, by means of the locking device 11, until the furnace needs re-coaling by furnace tender. 100

The locking device is indicated by the 105 number 11 as a whole, suspended from a beam as 24. In Figs. 2, 3, 4, the locking device is shown in detail to comprise an angular member comprising the horizontal tube 25 and the vertically arranged tube 26. In 110 the joint of the two tubes the pulley 27 is journaled on its pintle 28, and an upper pipe

- 29 with a flange 30 is attached to the device for supporting it. A guide pipe 31 may also be utilized if necessary for the chain 8 which passes through the angular member. 5 The open end of the tube 25 is flared as at 32 to guide the chain 8 and a fixed lug 33 is carried by the chain to pass through the flared opening and into the tube 25. A lug 25' in the tube 25 prevents the lug 33 on the 10 chain from passing too far toward the pulley 27 and avoids danger of jamming the lug in the pulley.
- A trigger or trip 34 having a weight 35 at its end is pivoted on its pintle 36 in the pair 15 of ears 37 depending from the under side of the tube 25, and this trip is formed with a beveled hooked end 38 which projects into the tube through the slot 39 in the under side of the tube and just in front of the ears 37.
- 20 The normal position of the trigger or trip is as shown in Fig. 2, but it will be understood that it may be turned on its pivot 36 by the passage over the beveled hook 38 of the lug 33 on the chain, as the rounded 25 end of the lug "rides down" the beveled hook in the slot 39. The weight 35 however is sufficient to restore the trip to its position as shown after the lug has passed over the beveled hook, and in this position the trip will 30 prevent movement of the chain to the left when the lug 33 encounters the hook 38 as in the position of Fig. 2.

Thus assuming the damper 4 to be open, and the lug 33 in position as shown in dotted 35 lines Fig. 2, now should the water rise in the tank the float 12 of course will rise with it. The chain is slack and this slack is taken up by the weighted lever 6 which swings on its pivot and closes the damper 4 while at 40 the same time pulling the chain to the right so that the lug rides down the beveled hook and passes over it to full line position. The trip now rights itself to position of Fig. 2 and the lug on the chain is prevented from 45 passing the trip because of the action illustrated. Thus although the float 12 should fall due to the action of the falling water level in the tank, it cannot overcome the load of the weight 6' because the lug 33 in its

engagement with the trip prevents the necessary pull on the chain to lift the weight 6'. In this manner the damper is locked in closed position and can only be released by withdrawal of the trip to permit passage of the lug 33 when fresh coal or a lively fire is wanted for a given time.

This automatic locking of the parts prevents and avoids the danger of the furnace tender leaving the damper wide open in the flue because of negligence or carelessness, and thus eliminates the possibility of fire to the dwelling and unnecessary consumption of fuel.

What I claim is:—

1. The combination in an automatic draft 65 regulator including an operation chain, of an angular, tubular, fixed guide member and a pulley therein for the chain, a lug fixed on the chain, said member being provided with a slot, and a weighted, pivoted trip formed 70 with a head projecting through said slot to coöperate with said lug, as described.

2. The combination, in a steam heating system with its damper, an equalizing tank containing water and a float in the tank controlling the damper, a chain operatively connecting the float and damper, a lug on the chain, and an automatic tripping device adapted to engage said lug and to hold said damper closed when abnormal pressure 80 arises.

3. The combination in a heating system with a damper, a controlling device for opening the damper, and a chain connecting said damper and device, a tubular guiding 85 support for the chain, a lug fixed on the chain, and a pivoted trip in the tubular support to coact with said lug to permit movement of the chain in opening the damper, but to prevent movement of the chain in reverse direction in order to hold the damper closed.

In testimony whereof I affix my signature in presence of two witnesses.

THOMAS J. CULLEN.
